LIQUID FILLED MAGNETIC COMPASS

Ladislav Kadlec, Lansdale, Pa., assignor to American Machine and Metals, Inc., New York, N. Y., a corporation of Delaware

Application May 4, 1954, Serial No. 427,636

1 Claim. (Cl. 33—223)

This invention relates to a compass and particularly 15 one suitable for use in aircraft or the like.

In a compass of the type concerned herein, it is desirable that the magnetic indicator means or card be one which is sensitive and yet not affected by vibration or shock. Furthermore, the compass is relatively small so 20 that parts must be compact yet access obtainable for servicing.

One of the objects of the invention is to provide an improved compass arrangement having the desired sensitivity and yet being substantially unaffected by shock 25 or vibration.

Another object of the invention is to provide an improved compass assembly arranged so that access can be obtained with ease to the various parts.

A still further object is to provide an improved means 30 for mounting the front transparent panel or glass.

In one aspect of the invention, the compass has a bowl or chamber for receiving the liquid, the bowl having a yieldable support therein upon which is mounted the floating card holding the magnets and which bears the 35 conventional indicia. An opening is located in the front of the bowl, said opening being closed by a transparent plate or panel through which the card or indicating means can be read. The frame of the compass may have an aperture or slot therein extending under the bowl for receiving an assembly including the compensating mechanism and a masking plate for the front of the compass. The transparent panel or glass closing the front aperture of the bowl may have a resilient metal seal ring which may be soldered at one edge to the glass and soldered 40 at its other edge to the margins of the bowl aperture. The glass thus will be resiliently supported and will not require a sealing ring and pressure to be applied thereto. Furthermore, the glass may be disassembled by merely heating the front of the bowl.

These and other objects, advantages and features of 50 the invention will become apparent from the following description and drawings.

In the drawings:

Fig. 1 is a sectional elevation.

Fig. 2 is a front view reduced in size.

Fig. 3 is a fragmentary front view with a portion of the card broken away.

Fig. 4 is an enlarged fragmentary broken section of the pivot support.

Fig. 5 is a fragmentary top view of the card assembly.

Frame 10 may have a bowl or chamber 11, said chamber 11 having a suitable compass fluid therein. The frame and bowl may be made of aluminum or other suitable non-magnetic material. Aperture 12 is at the front of slot 13 in the frame for receiving sub-assembly 14, said sub-assembly or carrier including a front masking plate 15 and the compensator assembly 16A.

The compensator assembly may be of any suitable type. The one illustrated includes two pairs of shafts located at right angles to each other, 17, 17 being one pair and the other pair being back of adjusting shaft 16. These shafts have transverse pieces of magnetized mate-

2

rial. The shafts can be adjusted, and thus the compensation, by turning adjusting screws under indentations 19B and 19C of cover plate 19D. When shaft 16 is turned by engagement of slot 19, worm 18 will turn meshed gears 18A and thus rotate shafts 17. Screw 19A holds cover 19D in place.

When it is desired to adjust or replace the compensating mechanism, it is possible to do so in the present invention by removing screws 20 and drawing the carrier sub-assembly 14 forwardly and out of slot 13 in main frame 10. Masking plate 15 is a part of the assembly.

A lighting arrangement is seen at 21, connection thereto being at 21A, such being described in detail in co-pending application Serial No. 421,332, filed April 6, 1954.

Bowl 11 has a front aperture 22 which can be closed by transparent panel 23 in a novel manner, such panel being glass or other suitable material. The panel or glass 23 has a C shaped or equivalently arranged flexible metal ring 24 which may be joined by soldering at edge 25 with the glass. Edge 26 can be joined to the margins of the bowl by soldering so as to form a fluid tight joint therewith. It can be seen that the mounting of the glass plate in the aperture does not require the usual gaskets and sealing mechanisms to hold it in place.

In assembling the parts, it is a simple matter to apply a soldering iron to the front of the frame 10 adjacent the aperture 22 so as to cause sufficient heat to be applied to effect soldering of ring 24 with its glass to the frame and thus close the front aperture of bowl 11.

In removing the glass, it is merely necessary to put the front of the casing on a hot plate.

Filling plug 27 can be provided in the top of the bowl. Cover 28 may be of suitable material held in place as desired by screws or in any other manner. Expansion capsules or bellows 29 communicate by means of passage 30 with the interior of bowl 11, the capsules providing an expansion chamber for the fluid in the bowl 11. Passage 30 is formed and located so that liquid flowing into the bowl from the bellows will be directed upwardly 40 and away from the float assembly 31. Such will tend to prevent undesirable eddies within the bowl.

A rubber line 32 is provided for receiving light through the port 33 in the manner described in said co-pending application Serial No. 421,332.

The float or card assembly 31 may comprise cup shaped card 34 which can have figures or indicia pressed therein, said figures being suitably filled with marking paint. By indenting the figures, the card is stiffened.

The float assembly can be carried on the doughnut or tore shaped float chamber 35, said float chamber being made in two parts 36, 37 as shown. The two parts of the float can be made of light metal and pressure welded or bonded to withstand fluid pressure. The magnetic supporting element 38 has a formed portion 39 to which the float assembly 37 with attached card 34 is assembled. Adjustable pivot member 40 can have screw threads thereon passing through nut 41, which is adjustable thereon, nut 42 being provided for holding the magnet supporting member 39 and the float assembly in adjusted position relative to each other. The height of the assembly relative to support 43 can be adjusted and the float assembly and card can be rotated relative to the magnet assembly 38 so as to suitably align these parts relative to each other.

Magnets 44 are carried by the magnet carrying member 38. It is to be noted that by the construction involved herein the magnets are relatively low in the bowl and that the center of gravity relative to the support can be adjusted with ease.

Pivot support 43 is arranged so as to hydraulically damp vibrations which might occur. This may be accomplished by providing a cylinder 45 carrying the pivot

seat 46, the cylinder 45 being slidably mounted on piston or plunger 47. Piston or plunger 47 is carried by screw threaded member 48. The screw threaded member 48 and the pivot can be inserted through the bottom of the bowl 11 and thus can be readily replaced or examined. Restricted aperture 49 is provided at the upper part of cylinder 45 so that fluid can flow in and out of the cylinder as the parts reciprocate. Thus, in case of vibration there will be a damping movement of the float assembly 31 relative to the frame. Conical spring 50 is arranged to urge the cylinder 45 upwardly relative to the piston 47, the spring and yieldable support being chosen so that the natural frequency of the bearing assembly is such that when subjected to movements within the frequency range of the aircraft contact will be maintained between the parts.

It should be apparent that variations may be made in details of construction without departing from the spirit of the invention except as defined in the appended claim.

I claim:

In a fluid compass, the combination including a fluid filled bowl, said bowl having a chamber with concave vertical walls, a magnetic card having a central hollow doughnut shaped float in said bowl supported on a pivot therein, a transparent panel in one wall of said bowl for 25

reading the card, and an expansion chamber connected to said bowl through a passage on one of said vertical concave faces of said chamber above said card, the outlet axis of said passage into said bowl being directed upwardly toward the roof of said chamber and away from said card.
